HANDLE FORMING TAPE

Joseph A. Young, Salt Lake City, Utah

Application August 11, 1943, Serial No. 498,217

2 Claims. (Cl. 229—52)

My invention relates to gummed tape of the type usually used for securing packages and has for its object to provide a new and novel method of employing the tape both to seal the package and provide a handle by which the package may be carried.

A further object is to provide a tape having perforated portions therein adapted to be torn when used to provide a handle for carrying the package and simultaneously seal the package.

These objects I accomplish with the device illustrated in the accompanying drawing, in which similar numerals and letters of reference indicate like parts throughout the several views and as described in the specification forming a part of this application and pointed out in the appended claims.

In the drawing

Figure 1 is a plan view of a roll of tape with one portion extended showing the perforated lines for making the handle.

Figure 2 is an edge view of a box or carton showing my tape in place thereon as used for a handle.

Figure 3 is an inverted plan view of a section of the tape showing the method of gumming the back side of the tape.

Figure 4 is a section of line 4—4 of Figure 1 with the additional feature of a reinforcing strip through the center and handle portion of the tape.

Figure 5 is a side view of the tape and handle as it would appear when used on a flat surface.

Figure 6 is a modified manner of manufacturing the tape.

In the drawing I have shown the roll of tape as A, and this roll may be used in the usual mechanical tape distributing machine now employed for that purpose. The tape is shown as B and is gummed along the two side portions 5 and 6, leaving the central portion 7 free from gum.

Spaced apart perforated lines 7 and 8 are formed in the tape with diagonal cuts 9 and 10 at one end of the lines 7 and 8. When torn or removed from the wetting machine the tape will appear having an end 12, side strips 13 and 14, a handle 15, and another end 16. A reinforcing strip 17 as shown in Figure 4 may be used under the handle 15 and this reinforcing may extend the full length of the tape if desired. The tape is applied to the package by adhering the end 12 and the side strips 13 and 14 to the package. Raising the end 16 will sever the perforated lines releasing the handle 15 and the operator may then adhere the end 16 over the ends of the side strips 13 and 14 in order to elevate the handle

15 and seal the package by use of the side strips 13 and 14.

It will be obvious that if desired the gumming of the back of the tape may be so placed that

5 the two side strips 13 and 14 may be left without any gum and the center strip used as the sealing means and the strips 13 and 14 used as double handles reversing the manner of applying the tape.

10 In Figure 6 I have shown a modified type of the invention in which the tape is shown as C, which is gummed over its entire back surface and which tape carries a medial longitudinal wire or plastic handle member 20. The tape is perforated on an

15 angle at 18 and 19 extending inwardly to a central perforation 21 which extends longitudinally of the tape in alignment with the handle member 20. When employing this type of handle

means the entire surface of the tape is dampened and the portions 22, 23 and 24 are adhered to the package with the end 25 loose and used to manipulate the tape. The wire strip or member

20 is elevated by raising the end 25 automatically perforating the lines 18, 19 and 21, forming a loop

25 of the handle member 20 by moving the end 25 toward the end 24 and end 25 is then adhered down onto the ends of the members 23 and 24.

Having thus described my invention I desire to secure by Letters Patent and claim:

30 1. A tape of the class described comprising a roll of tape having two side portions throughout its entire length carrying adhesive and a multiplicity of spaced apart rows of parallel perforations spaced from the longitudinal edges of said

35 roll one end only of each row of perforations being extended out at an angle to the edge of said roll said tape to be torn off to form an individual section each section having an end portion adapted to be secured to a package with the

40 perforate sides to be secured to the package and the intermediate portion raised as a handle, the extreme end being secured down onto the package over the spaced apart sides after the handle has been elevated.

45 2. A handle forming tape comprising a roll of tape having parallel rows of perforations formed therein of equal length and spaced equally from the outer longitudinal edges thereof with one end only of each row of perforations angled out to the longitudinal edge adjacent thereto to provide

50 for severing of the two sides from the central portion with the central portion to be elevated by drawing the two ends thereof toward each other to form a handle with the two sides adhered overlapping the body of the tape when affixed to a package.

JOSEPH A. YOUNG.
